CONTAINER FOR COMBINED RAZOR BLADES AND MOUNTS

Glynne F. Clifford, Staines, Middlesex, England, assignor
to Wilkinson Sword Limited, London, England, a British
company

Filed Feb. 26, 1969, Ser. No. 15,920

Claims priority, application Great Britain Aug. 27, 1968

Term of patent 14 years

Int. Cl. D9—04

U.S. Cl. D9—193

Fig. 1.

Fig. 2.

Fig. 3.

Fig. 4.

FIG.1 is a perspective view of a container for combined razor blades and mounts showing my new design;

FIG. 2 is a side elevational view;

FIG. 3 is an end elevational view showing the end opposite that seen in FIG. 1; and

FIG. 4 is a bottom plan view thereof.

I claim:

The ornamental design for a container for combined razor blades and mounts, as shown.
